UNITED STATES PATENT OFFICE.

SEWARD W. HECOX, OF ZEELAND, MICHIGAN.

DESIGN FOR A PHONOGRAPH-CABINET.

56,232.

Specification for Design. Patented Aug. 31, 1920.

Application filed June 17, 1920. Serial No. 389,773. Term of patent 7 years.

To all whom it may concern:

Be it known that I, SEWARD W. HECOX, a citizen of the United States, and a resident of Zeeland, county of Ottawa, and State of Michigan, have invented a new, original, and ornamental Design for Phonograph-Cabinets, of which the following is a specification, reference being had to the accompanying drawing, forming a part hereof, which is a front perspective showing my new design.

I claim:

The ornamental design for a phonograph cabinet, as shown.

SEWARD W. HECOX.
